(57) **CLAIM**

The ornamental design for a collapsible container, as shown and described.

DESCRIPTION

FIG. 1 is a perspective view of a collapsible container according to an embodiment of the present invention;

FIG. 2 is an enlarged perspective front top view of a front side of the collapsible container shown in FIG. 1;

FIG. 3 is an enlarged perspective front bottom view of the front side of the collapsible container shown in FIG. 1;

FIG. 4 is an enlarged front elevational view of the front side of the collapsible container shown in FIG. 1;

FIG. 5 is a cross-sectional view of the front side of the collapsible container taken along line 5—5 as shown in FIG. 1;

FIG. 6 is a perspective view of a collapsible container according to another embodiment of the present invention;

FIG. 7 is an enlarged perspective front top view of a front side of the collapsible container shown in FIG. 6;

FIG. 8 is an enlarged perspective front bottom view of the front side of the collapsible container shown in FIG. 6;

FIG. 9 is an enlarged front elevational view of the front side of the collapsible container shown in FIG. 6; and,

FIG. 10 is a cross-sectional view of the front side of the collapsible container taken along line 10—10 as shown in FIG. 6.

The broken lines shown herein for illustrative purposes of the environment or which define the bounds of the claimed design form no part of the claimed design.
